United States Patent Office

Des. 206,783
Patented Jan. 31, 1967

206,783

SIGN HOLDER

Daniel M. McCormick, 7845 Alderman Road,
Jacksonville, Fla. 33211

Original design application July 19, 1965, Ser. No. 86,444.
Divided and this application Dec. 20, 1965, Ser. No.
508

Term of patent 14 years

(Cl. D1—3)

FIG.1

FIG. 2

FIG. 3

FIG. 4

FIG. 5

FIG. 6

FIG. 7

FIG. 8

FIG. 1 is a front perspective view of a sign holder showing one embodiment of my new design;

FIG. 2 is a front elevational view thereof;

FIG. 3 is a right side elevational view thereof;

FIG. 4 is a bottom plan view thereof;

FIG. 5 is a front perspective view of a sign holder showing another embodiment of my new design;

FIG. 6 is a front elevational view thereof;

FIG. 7 is a bottom plan view thereof; and

FIG. 8 is a left side elevational view thereof.

This application is a division of copending application Serial No. D. 86,444, filed July 19, 1965. Application Serial No. D. 86,444, was a continuation-in-part of my application Serial No. D. 80,247, filed June 2, 1964, now abandoned.

I claim:

The ornamental design for sign holder, substantially as shown and described.
